ABSTRACT

An electrically powered furnace for melting high-melting point materials in the vacuum and zero gravity environment of space comprising an alumina crucible, cylindrical in shape, and enclosing a cylindrical tantalum sample holder that contains the sample to be melted. The crucible is surrounded by concentric cylindrical enclosures made of polished sheet molybdenum. The sample holder is clamped between a pair of round plates and a pair of alignment bolts are joined to the circular plates and extend along the longitudinal axis of the furnace through the end covers of the crucible and surrounding concentric enclosures.

HIGH-TEMPERATURE FURNACE FOR MELTING MATERIALS IN SPACE

ORIGIN OF THE INVENTION

The invention described herein was made by an employee of the United States Government and may be manufactured and used by or for the Government for governmental purposes without the payment of any royalties thereon or therefor.

BACKGROUND OF THE INVENTION

This invention relates generally to high temperature furnaces and more particularly to a furnace for melting high melting point materials in the vacuum and zero gravity environment of space.

Preparation for various long duration earth-orbiting space flights programmed for the future includes the development of a variety of devices particularly suitable for use in the vacuum and zero gravity environment of space. Such devices will be required in performing many tests and experiments planned aboard earth-orbiting workshops, laboratories and space stations that will remain in earth orbit for long periods.

Included in the projects to be undertaken in earth orbit are experiments relating to manufacturing in space. The advantages of using the space environment for carrying out certain manufacturing processes is well recognized and it is anticipated that some day many unique products will be made in space. These products will be made by processing materials in the fluid state since it is in this state that materials will be affected by the vacuum and zero gravity condition in space.

In conducting experiments to observe and analyze the behavior of various materials in space and thereby gain knowledge that will contribute to the development of space manufacturing, furnace devices capable of melting the materials under study will be needed aboard the orbiting space vehicles. Such a furnace device should be highly efficient so as not to require undue power, and the furnace must be constructed so as to not be impaired by the high "g" forces experienced during certain phases of a space flight, for example, the launch phase.

Although high temperature furnaces of various designs are known, they are not deemed to have the structural rigidity and performance efficiency required for use in a space facility.

SUMMARY OF THE INVENTION

The invention comprises an electrically powered furnace for melting materials in the vacuum and zero gravity environment of space. The furnace includes a crucible of refractory material enclosing a sample holder adapted for containing the sample to be melted. The crucible is surrounded by a plurality of spaced, concentrically related, polished sheet enclosures, preferably of molybdenum, for preventing radiation loss from the crucible. To provide firm support for all the parts of the furnace and insure that the furnace will withstand high "g" forces the sample holder is clamped between a pair of opposed plates and a pair of alignment bolts are joined to the plates and extend along the longitudinal axis of the furnace through opposite ends of the crucible and polished sheet enclosures. The alignment bolts provide connections for rigidly mounting the furnace aboard a spacecraft in communication with the vacuum environment of space.

Accordingly, it is a general object of the present invention to provide a means for melting materials in the vacuum and zero gravity environment of space.

A more specific object of the invention is to provide a highly efficient, low powered, furnace for melting samples of high melting point materials aboard an earth-orbiting spacecraft.

Another object of the invention is to provide a high temperature furnace for installation on a space vehicle and constructed so that it will withstand the high "g" forces attendant to certain phases of space flight.

These and other objects and advantages of the invention will become apparent upon reference to the following specification, attendant claims and drawing.

BRIEF DESCRIPTION OF THE DRAWING

FIG. 1 is a vertical sectional view of a high temperature furnace embodying the invention.

FIG. 2 is a sectional view taken along line 2-2 of FIG. 1.

DESCRIPTION OF THE PREFERRED EMBODIMENT

Referring to FIGS. 1 and 2, therein is shown a high temperature furnace 11 particularly adapted for installation on a 10 spacecraft for melting samples of high-melting point materials in the vacuum and zero gravity environment of space. The furnace 11 comprises an alumina cylindrical crucible 13 located centrally of the furnace. The crucible has an integral bottom 15 and a separate cover 17 fitted and joined to the main body 15 of the crucible at the upper end. Formed in the opposite end edges of the crucible 13 are a series of vertical slots 19 arranged in spaced pairs to receive tungsten electric resistance heating wire 23 that is looped around spaced supports 25 between the slots 19. In the embodiment illustrated the wire supports 25 are provided every 60° radially and the supports at one end of the crucible are staggered relative to the supports at the other end thereof. The wire is arranged around the crucible 13 extending diagonally between upper and lower ends and being looped around the supports 25, alternately, at the upper and lower ends. Lead wires 27 for the heating wire 23 extend from a power source (not shown) and enter the crucible 13 through a double-bore alumina tube 29 that is bonded in an opening 33 by a temperature-resistant cement. Another tube 29 is sealed in an opening 34 at the lower end of 20 the crucible for receiving lead wires 35 of a thermocouple 37 associated with an indicator (not shown) for indicating temperature within the crucible 13.

Surrounding the crucible 13 are four concentrically related 30 cylinders 41, 43, 45 and 47 of uniformly increasing diameter and length. The cylinders are provided, respectively, with circular end covers 49, 51, 53 and 55 that fit telescopically over the ends of the cylinders. The cylinders and covers are made of polished sheet molybdenum that reflect heat to prevent radiation loss from the crucible 13. The covers are not sealed 35 to the cylinders so that gas trapped within each of the cylinders will escape when the furnace is placed in a vacuum environment and thereby assure against convection heat loss between the cylinders and the crucible. The alumina tubes 29 containing the lead wires 27 and 35 pass through vertically aligned holes 57 in the lower covers 49, 51, 53 and 55 and a high-temperature sealing cement is used to provide a seal around the holes 57.

Centered within the crucible 13 is a cylindrical sample 40 holder 61 made of tantalum and including top and bottom covers 63 joined by welding to the opposite ends of the cylinder to provide a sealed container for a sample 65 of material such as glass, for example. The sample 65 is indicated in phantom lines in its solid state and a spherical mass 67 45 represents the sample after being melted. Surrounding the sample 65 is a carbon cylinder 69 and end covers 71. Each of the carbon end covers 71 has a central pointed projection 73 that engages the sample 65 to support the sample until it is melted. When the sample is melted it will have no tendency to 50 adhere to the carbon and will readily pull away from the carbon projections 73 and form the sphere 67 without contamination of the sample.

The sample holder 61 is clamped between a lower circular 55 plate 75 and an upper circular plate 77. Each of the plates are made of molybdenum and the lower plate 75 has a circular recess 79 therein that receives the lower end of the sample holder 61. Three molybdenum clamping bolts 81 each have threaded end portions 83 of reduced diameter extending 60 through vertically aligned holes 85 in the upper and lower plates. Nuts 91 are used in clamping the sample holder 61 firmly between the plates 75 and 77.

Joined to each of the plates 75 and 77 is a molybdenum bolt 93. The bolts 93 are located on the vertical or longitudinal axis of the furnace 11 and have a threaded portion 95 screwed into 65 a threaded hole 97 in the center of the plates 75 and 77. The

two bolts 93 extend in opposite directions from the plates 75 and 77 through vertically aligned holes 99 in the top and bottom of the crucible 13 and in the top and bottom covers of the cylinders 41, 43, 45, and 47. Each bolt 93 has an unthreaded portion 101 of increased diameter that provides a spacer between the respective plates 75 and 77 and the upper and lower ends of the crucible 13. Spacers in the form of molybdenum nuts 103 threaded on the bolts 93 are also provided between the upper and lower ends of the crucible 13 and between the respective adjacent covers 49, 51, 53 and 55. Nuts 103 are also threaded on the bolts 93 against the outer surfaces of the covers 55.

The furnace 11 may be mounted in a spacecraft in the manner desired and may be enclosed in a chamber 105 (indicated in phantom line) that is put in communication, selectively, with the vacuum environment of space. Mounting elements 107 may be attached to the bolts 93 and to the chamber 105.

The high temperature furnace disclosed herein is extremely efficient in that heat losses from the crucible are minimal and the described structure of the furnace makes it uniquely sturdy and resistant to damage from subjection to high "g" forces.

I claim:

1. A furnace for melting materials in the vacuum and zero gravity environment of space comprising:
an enclosed container for holding a sample of material to be melted;
said container being disposed between two clamping plates; adjustable means extending between said plates for clamping said plates against said container;
a plurality of concentrically related enclosures surrounding said container;
a bolt connected to each of said plates, said bolts being aligned with each other and extending outwardly and axi-

ally of said container and said furnace;
said bolts passing through opposite walls of said concentrically related enclosures;
spacers carried by said bolts between adjacent walls of said concentrically related enclosures;
electrical conducting means disposed in the vicinity of said enclosed container for electrically heating a sample of material to be melted.

2. The invention as defined in claim 1 wherein the innermost of said concentrically related enclosures comprises an alumina crucible, said electrical conducting means comprising electric resistance wire, said wire being arranged within said crucible.

3. The invention as defined in claim 2 wherein said crucible is cylindrical, a plurality of slots circumferentially spaced around each end portion of said crucible, said resistance wire extending diagonally between opposite ends of said crucible and being supported in said slots.

4. The invention as defined in claim 1 wherein said bolts are threadedly joined to said clamping plates in the center of said plates, said spacers threadedly engaging said bolts.

5. The invention as defined in claim 4 wherein said plates and said bolts are molybdenum.

6. The invention as defined in claim 1 wherein said concentrically related enclosures comprise a plurality of cylinders having separable end covers, said cylinders and said covers comprising polished sheet molybdenum.

7. The invention as defined in claim 1 wherein said enclosed container comprises an interior carbon lining.

8. The invention as defined in claim 7 wherein said lining comprises opposite spaced projections for supporting a sample of material prior to melting of the material.
